UNITED STATES PATENT OFFICE.

WILLIAM H. CRIBBEN, OF CHICAGO, ILLINOIS.

DESIGN FOR A STOVE.

SPECIFICATION forming part of Design No. 34,978, dated August 20, 1901.

Application filed July 18, 1901. Serial No. 68,854. Term of patent 7 years.

To all whom it may concern:

Be it known that I, WILLIAM H. CRIBBEN, a citizen of the United States, and a resident of Chicago, in the county of Cook and State 5 of Illinois, have invented and produced a new and useful Design for a Stove; and I do hereby declare that the following is a specification thereof, reference being had to the accompanying drawings, which form a part thereof.

In the drawings, Figure 1 is a perspective view of a stove embodying my invention. Fig. 2 is an end elevation of the same.

Said design is shown embodied in a cook stove or range of a familiar type provided 15 with a reservoir having the end thereof ornamented to correspond with the ornamentation of the stove, which consists of rosettes and scrolls in relief. Said reservoir end is provided with a central rosette and with scrolls 20 surrounding the same.

The oven-door is provided with a central raised panel-piece designed to serve as a name-plate. It is also provided in its upper corners with a rosette in relief, about which and 25 at the ends and at the bottom of the door are scrolls also in relief.

The design for the fire-door corresponds generally with the ornamentation on the oven-door and reservoir end. The parts surround- 30 ing the same are ornamented in relief by scrolls and rosettes.

The end door and its members are provided with a scroll in relief extending longitudinally of the door across the entire top thereof 35 and scrolls also in relief surrounding the damper-apertures extending therethrough. Similar scrolls are also provided around the upper damper-apertures near the top of the stove.

The side of the stove adjacent to said ornamented oven-door is also ornamented with 40 scrolls in relief, and a shelf or ledge extends longitudinally of the stove beneath the oven-door and projects outwardly therefrom, as shown in Fig. 1.

A shelf of the ordinary or usual form is supported upon an ornamental shelf-base secured 45 at the side of the stove opposite the ornamented side thereof. Said shelf-base is provided above and below the shelf with rosettes and scrolls in relief corresponding generally 50 with the design of the oven-door and comprising a central rosette and rosettes in the upper corners thereof and a symmetrical arrangement of scrolls surrounding said rosettes at the sides and bottom of the base. 55 Above the shelf said base extends upwardly and is also provided with symmetrical scrolls, as shown in the drawings. Brackets of the usual form are secured one on each edge of said shelf-base. The legs and the frame connecting the same are provided with raised figures corresponding generally to the ornamentation of the stove as a whole and as shown in the drawings.

Having described my new design, what I 65 claim as new, and desire to secure by Letters Patent, is—

The design for a stove or range, substantially as shown and described.

In testimony whereof I have hereunto sub- 70 scribed my name in the presence of two subscribing witnesses.

WILLIAM H. CRIBBEN.

In presence of—

LOUIS J. DELSON,
ANNA B. HILLS.
